UNITED STATES PATENT OFFICE.

CHARLES W. WIPFLER, OF DETROIT, MICHIGAN.

DESIGN FOR AN OIL-STOVE.

SPECIFICATION forming part of **Design No. 22,710**, dated **August 15, 1893**.

Application filed July 17, 1893. Serial No. 480,759. Term of patent 14 years.

To all whom it may concern:

Be it known that I, CHARLES W. WIPFLER, a citizen of the United States, residing at Detroit, in the county of Wayne and State of Michigan, have invented and produced a new and original Design for Oil-Stoves, of which the following is a specification, reference being had to the accompanying drawing, showing a perspective view of a stove embodying my design.

The stove comprises a base, a burner section and a radiator section.

The base A is substantially rectangular having ornamental side panels B and terminating at its lower edge in an ornamental scroll border C, from the corners of which the legs depend.

The burner section D contracts in a graceful

curve from the bottom of the base to its top, is substantially square and on each face is a ²⁰ deep seated window surrounded by an outwardly flaring fan shaped window frame, the corners or posts E between the windows being ornamented.

The top or radiator section F is of cylindrical shape and terminates in an ornamental cap G and central dome H.

What I claim as my invention is—

The design for oil stoves herein described and shown.

In testimony whereof I affix my signature in the presence of two witnesses.

CHARLES W. WIPFLER.

Witnesses:

M. B. O'DOGHERTY,

OTTO F. BARTHEL.
